(57) **CLAIM**

The ornamental design for a hybrid pulse measuring device, as shown and described.

DESCRIPTION

FIG. 1 is a perspective view of the hybrid pulse measuring device according to the present invention;

FIG. 2 is a front view of the hybrid pulse measuring device of FIG. 1;

FIG. 3 is a rear view of the hybrid pulse measuring device of FIG. 1;

FIG. 4 is a left side view of the hybrid pulse measuring device of FIG. 1;

FIG. 5 is a right side view of the hybrid pulse measuring device of FIG. 1;

FIG. 6 is a top view of the hybrid pulse measuring device of FIG. 1; and,

FIG. 7 is a bottom view of the hybrid pulse measuring device of FIG. 1.
